VARIABLE OUTLET GAS BURNER

Paul F. Swenson, Cleveland Heights, and Milton F. Pravda, Bedford, Ohio, assignors to The Cleveland Research Corporation, Cleveland, Ohio, a corporation of Ohio

Application July 7, 1948, Serial No. 37,347

22 Claims. (Cl. 158—117)

1

This invention relates to gas burners of the mixing type having simultaneously operated controls for controlling a velocity gas stream being supplied and for controlling the resulting gas and air mixture and relates, more particularly, to an improved construction enabling a burner of this type to operate efficiently on various gaseous fuels of different B. t. u. values.

Gas burners as heretofore used have been built to suit the requirements of the particular gaseous fuel which is available for the burners and when a change is made from one type of gaseous fuel to another, such as from natural gas to artificial gas or vice-versa, or when a gas stove or the like embodying burners built for one type of gas is sold for use in a location having another type of gas, it has been necessary to alter the burners accordingly. These alterations can sometimes be made by drilling out certain openings of the burners but in other cases may require the substitution of different burner parts or of a completely different burner assembly. Furthermore, these alterations usually require the services of skilled workmen and also make it necessary for stove dealers to carry supplies of such different burners and different burner parts in stock.

An important object of the present invention is to eliminate this troublesome situation and, in so doing, provides an improved gas burner construction such that the same identical burner will operate in a safe and efficient manner and with a very satisfactory turndown ratio for any one of numerous different gaseous fuels having widely varying B. t. u. values, without requiring any substitution or alteration in any of the burner parts.

Another important object of this invention is to provide a simple and compact gas burner in which the velocity discharge of gas and the delivery of the gas and air mixture are varied simultaneously by novel means so as to produce an efficient, safe and reliable functioning throughout the entire range of burner operation.

Still another object of this invention is to provide an improved gas burner of the type utilizing the velocity discharge of gas from a valve opening or orifice to produce a gas and air mixture and in which the valve opening or orifice is such that the flow capacity thereof will be self-adjusting to substantially suit the B. t. u. value of the particular type of gas being supplied.

A further object is to provide an improved gas burner of this character in which the gas delivery orifice is of a diverging shape in the direction of valve-opening movement such that it will

2

increase progressively in size in two different directions during the opening or uncovering thereof by the actuation of the valve.

Another object is to provide an improved gas burner of the mixing-tube type having a gas control valve for controlling the velocity gas discharge and a movable shutter means for controlling the delivery of the gas and air mixture and in which novel means is employed for actuating said control valve and shutter means from a single control shaft.

Yet another object is to provide an improved gas burner of the character mentioned in which adjusting means of a novel construction permits the control valve actuation to be calibrated relative to the actuation of the shutter means so that efficient combustion of the gas as well as a safe and satisfactory operation of the burner will be readily obtainable.

As a further object, this invention provides an improved gas burner of the mixing-tube type embodying a pair of control devices comprising a valve for controlling the velocity gas discharge and a shutter means for controlling the delivery of the gas and air mixture, and in which a single control shaft has both rotary and axial movement, of which the rotary movement is utilized to actuate one of said control devices and the axial movement is utilized to actuate the other control device.

It is also an object of this invention to provide an improved gas burner which includes a pilot burner having a novel gas filtering means.

Still another object is to provide an improved gas burner of the character mentioned in which the mixing tube is mounted in upright relation on a frame having spaced upright arms and the actuating means for the control devices of the burner are mounted on one of the upright arms and a pilot burner is mounted on the other upright arm.

Yet another object is to provide an improved gas burner of the character referred to in which the frame of the burner has a lateral arm portion connecting the spaced upright arms and on which the orifice is located in cooperating relation to the lower end of the mixing tube and is adapted to be supplied with gas from a valve chamber contained in such lateral arm portion.

A further object is to provide an improved gas burner of the character mentioned which can be economically manufactured and is well suited for use on stoves and the like and which can be easily disassembled for cleaning purposes.

An additional object of this invention is to

provide an improved gas burner of the kind indicated in which adjustable means of a novel form is employed for controlling the air intake and in which the removal and replacement of the burner tube can be readily accomplished without disturbing the adjustment of such air intake control means.

The invention can be further briefly summarized as consisting in certain novel combinations and arrangements of parts hereinafter described and particularly set out in the claims hereof.

In the accompanying sheets of drawings:

Fig. 1 is a top plan view of a gas burner embodying the present invention;

Fig. 2 is a vertical section taken therethrough substantially on line 2—2 of Fig. 1;

Fig. 3 is a side view of the burner as seen from the control side thereof but with the control handle omitted;

Fig. 4 is a partial vertical section taken through the burner on line 4—4 of Fig. 2;

Fig. 5 is a partial transverse section taken substantially on line 5—5 of Fig. 2;

Fig. 6 is a fragmentary plan view on an enlarged scale showing the gas control valve and the gas discharge orifice thereof;

Fig. 7 is a fragmentary vertical section on an enlarged scale taken longitudinally through the gas control valve, as indicated by line 7—7 of Fig. 6;

Fig. 8 is a fragmentary vertical section on an enlarged scale taken transversely of the gas control valve, as indicated by line 8—8 of Fig. 6;

Fig. 9 is a fragmentary vertical section taken through the supply end of the gas control valve, as indicated by line 9—9 of Fig. 2;

Fig. 10 is a transverse section taken through the burner tube and shutter member, as indicated by line 10—10 of Fig. 2;

Fig. 11 is a side view showing one of the air intake control members in detached relation;

Fig. 12 is a vertical section similar to Fig. 2, but showing a modified form of gas burner;

Fig. 13 is a fragmentary transverse section taken on line 13—13 of Fig. 2;

Fig. 14 is a fragmentary vertical section taken on line 14—14 of Fig. 13;

Fig. 15 is a partial vertical section taken through one of the pilot burners and the adjacent portion of the main burner, as indicated by line 15—15 of Fig. 12;

Fig. 16 is a fragmentary vertical section taken through the supply end of the gas control valve, as indicated by line 16—16 of Fig. 12;

Fig. 17 is a partial transverse section taken on line 17—17 of Fig. 12 and showing the adjustable fulcrum of the actuating means for the gas control valve;

Fig. 18 is a vertical section similar to Fig. 2, but showing another modified form of gas burner;

Fig. 19 is a partial plan view of the modified burner of Fig. 18; and

Fig. 20 is a transverse section taken on line 20—20 of Fig. 18.

Proceeding now with a more detailed description of the invention and referring first to the preferred embodiment illustrated in Figs. 1 to 11 inclusive, the burner 10 comprises a support or base 11 and a gas and air mixing tube 12 mounted thereon in upright relation. The burner also embodies a control shaft 13 and a pair of control devices comprising a gas control valve 14 and a shutter member 15. As explained in detail hereinafter, the shaft 13 causes actuation of the valve 14 so

as to control the delivery of a velocity stream of gas to the tube 12 from a metering port or orifice 16a and also actuates the shutter member 15 for varying the size of the combustion opening 17 from which the gas and air mixture is delivered for burning as a sustained flame.

The support 11 is here shown as comprising a one-piece frame having laterally spaced upright arm portions 18 and 19 and a laterally extending arm portion 20 which integrally connects the upright arm portions at their lower ends. The gas control valve 14 is located in the lateral arm portion 20 of the frame and for this purpose the lateral arm portion is provided with a bore or valve chamber 21 which extends longitudinally therein. The orifice 16a is adapted to be supplied with gas from the valve chamber 21 and is defined by the uncovered portion of a radial hole 16 located at the top of the lateral arm portion 20 at a point substantially midway between the upright arm portions 18 and 19. The hole 16, and hence the size of the orifice 16a is controlled by a valve member 22 which is reciprocably movable in the valve chamber 21.

The frame 11 is provided on one side thereof with a tapped opening 23 through which gas of suitable characteristics is supplied to the burner from an appropriate source as by means of the pipe or conduit 23a. The threaded opening 23 communicates with an inlet chamber 24 from which the gas is supplied to the valve chamber 21 through the central passage 25 of a sleeve 26 which is mounted in the inlet end of the valve chamber and extends longitudinally thereof to a point adjacent the hole 16. Gas is supplied to the sleeve passage 25 from the inlet chamber 24 through the radial port 27 of the sleeve 26. The inner end of the sleeve 26 forms a valve seat 28 surrounding the passage 25 and adapted to be engaged by an end of the valve member 22 as will be explained in greater detail hereinafter. The outer end of the sleeve 26 constitutes a screw plug portion 26a which closes the outer end of the valve chamber 21.

The control valve 14 also includes a valve stem 30 on the inner end of which the valve member 22 is mounted as by means of the screw 31 and whose outer end projects from the valve chamber 21 through the bushing 32 for connection with the valve actuating mechanism to be described hereinafter. The valve member 22 is urged toward engagement with the valve seat 28 by means of a compression spring 33 disposed around the valve stem 30. The spring 33 has one end thereof in engagement with the bushing 32 and its other end in engagement with a spring seat 34 which is in the form of a shoulder or collar surrounding the inner end of the valve stem and engaging the adjacent end of the valve member 22.

The burner tube 12 comprises a metal tube or sleeve having a central passage 36 extending axially therethrough. The tube is mounted on the frame 11 by having its lower end snugly received between the upright arm portions 18 and 19. The arm portion 19 has an upright arcuate bearing surface 37 thereon for cooperation with one side of the burner tube 12 and the upright arm portion 18 has a movable detent 38 therein for engagement with the opposite side of the burner tube. At or adjacent the lower end of the upright arcuate bearing surface 37 the arm portion 19 is provided with a stop element in the form of a shoulder 39 which is adapted to be engaged by the lower end of the burner tube 12 for spac-

ing such lower end above the top of the lateral arm portion 20. The spacing of the lower end of the burner tube above the lateral arm portion 20 provides an air inlet opening 40, or a pair of such openings at opposite sides of the frame 11, for admitting air to the lower end of the burner tube.

The upright arcuate bearing surface 37 of the arm 19 preferably has a smaller radius of curvature than the burner tube 12 so that the wall of the burner tube will be engaged only along axial lines at arcuately spaced points thereof, as indicated at 37a and 37b in Fig. 1. The detent 38 is here shown as having a substantially cone-shaped tip 38a which is engageable in an external annular groove 12a provided on the burner tube 12 adjacent the lower end thereof. The detent 38 is urged in a direction for the engagement of its pointed end 38a in the groove 12a by means of the compression spring 41.

The burner 10 is provided at the upper end thereof with a cap 43 which is spaced from the upper end of the burner tube 12 so as to define therewith the annular discharge opening or combustion orifice 17 from which the gas and air mixture issues for burning as a sustained flame, as mentioned above. The cap 43 is a disk-like member which, in this instance, is mounted on the burner tube 12 by means of the central post 44 and the transverse rib 45. The upper end of the burner tube preferably has an outturned annular bead or flange 46 thereon forming a guide means for the upper end of the shutter member 15.

The shutter member 15 is in the form of a sleeve which extends coaxially with the burner tube 12 and is disposed in telescoping relation therearound. The shutter member is movable axially of the burner tube by mechanism to be presently described so that the upper end thereof is movable toward and away from the cap 43 for controlling the size of the delivery opening 17.

From the construction and arrangement of the parts embodied in the burner 10 as thus far described, it will be seen that the burner tube 12 is mounted on the frame 11 so as to extend in vertical relation over the discharge orifice 16a of the gas control or metering valve 14. The discharge of a velocity stream of gas upwardly into the burner tube 12 by the orifice 16a induces a flow of combustion air into the lower end of the burner tube through the air inlet openings 40. The air becomes thoroughly mixed with the gas stream to produce a gas and air mixture stream which flows upwardly through the passage 36 of the burner tube and is discharged through the combustion opening 17. Since the shutter member 15 controls the size of the delivery opening 17 it also controls the amount of air which will be drawn into the burner tube through the opening 40 by the gas stream.

The control shaft 13 is mounted in the upright arm portion 18 of the frame 11 and includes a plain shaft portion 47 and a threaded shaft portion 48. The threaded shaft portion 48 operates in a threaded opening of the arm portion 18 so as to cause axial movement to be imparted to the shaft 13 during rotation thereof. The inner end of the shaft 13 extends into a space 49 located between the burner tube 12 and the upright arm portion 18 and has a rotary cam 50 mounted thereon. The inner end of the shaft is here shown as being a reduced portion 51 of square or other non-circular form on which the cam 50 is secured by means of the head 52. The shaft 13 is provided at its outer

end with an extension shaft 53 which is connected therewith by means of the sleeve adapter 54. The extension shaft 53 has a suitable knob or handle 55 mounted thereon which is adapted to be grasped for manual actuation of the shaft 13.

The cam 50 cooperates with a cam follower 56 which is connected with the shutter member 15 so that rotation of the shaft 13 in a counter-clockwise direction, such as is customarily used in turning on a gas burner, will cause lowering of the shutter member by the cam to enlarge the delivery opening 17. During rotation of the shaft 13 in a clockwise direction the cam 50 acts to lift the shutter member 15, thereby decreasing the size of or closing the delivery opening 17. The cam 50 is of an appropriate shape or contour to produce the desired variation in the delivery opening 17 in relation to the rotary actuation of the shaft 13.

The axial movement imparted to the control shaft 13 by the threaded shaft portion 48 is utilized for actuating the gas control valve 14 and for this purpose a lever 57 is disposed so as to form an operating connection between the control shaft and the valve actuating stem 30. The lower end of the lever 57 has a forked portion 57a which straddles the outer end of the valve stem 30 and is engaged by the rounded portion 58a of an adjusting nut 58. The nut 58 is mounted on a threaded portion 59 of the valve stem 30 so as to form a shoulder thereon for cooperation with the forked end of the lever 57.

The upper end of the lever 57 also has a forked portion 60 which straddles the control shaft 13 and carries a pair of lugs 60a which extend axially of the shaft at opposite sides thereof. A collar 61 loosely surrounding the shaft 13 has a transverse groove 61a in the exposed face thereof in which the axial lugs 60a of the forked end 60 engage. The collar 61 is mounted on a reduced end portion 54a of the connector sleeve 54 so that rotation of the latter with the shaft 13 will be permitted while the collar is held against rotation by the lugs 60a.

At a point intermediate its ends the lever 57 engages a fulcrum 62 on which the lever is rockable. The fulcrum 62 is here shown as being a round bar extending through the vertical slot 63 of the upright arm 18 of the frame 11. The fulcrum 62 is vertically adjustable in the slot 63 for varying the lever arm values of the lever 57 and, for this purpose, the arm portion 18 is provided with a vertical adjusting screw 64 which is rotatably mounted in unthreaded openings 64a and 64b thereof and extends through a threaded opening 62 of the fulcrum. The adjusting screw 64 may be provided at its lower end with a friction nut 65, or the like, for holding the screw against rotation when the fulcrum has been shifted to a desired position of adjustment.

With the construction and arrangement just described above for the lever 57, it will be seen that when the control shaft 13 is rotated in the above-mentioned counter-clockwise direction to turn on the burner 10, the threaded shaft portion 48 will cause an inward axial movement of the control shaft, that is to say, movement toward the left as seen in Fig. 2, thereby imparting rocking movement to the lever 57 in a direction to cause opening movement of the valve member 22 in opposition to the spring 33. When the shaft 13 is rotated in a clockwise direction to shut off the burner 10, or lower the flame thereof, the lever 57 is rocked in the opposite direction

and permits the spring 33 to shift the valve member 22 toward engagement with the valve seat 28.

The defining surface characteristics of the gas delivery orifice of the control or metering valve 14, as shown (Figs. 6, 7 and 8), and those of the cooperating elements of the valve, especially from the standpoint of suiting the burner to gaseous fuels having widely varying B. t. u. values, are highly important. The construction aims to provide an extremely simple and easily made metering valve by which a single concentrated, approximately constant velocity, stream of nearly uniform cross-section is directed into the air inlet end of the mixing tube substantially parallel to and fairly near its axis at all settings of the valve down to its minimum usable gas discharge port or orifice size (something less than fully closed).

With the above in view, the metering gas discharge port 16a afforded by the fixed wall of the hole 16 in body or base 20 in cooperation with the valve member or plug 22 (the metering edge of which varies the port or effective orifice size) is enabled, among other features, to be of similar shape in the various valve settings (area varying in two directions) and with practically a minimum of peripheral surface extent length-wise of the gas stream, by making the portion of the port which is formed in the valve body as straight relatively converging, thin edged, sides 67 which preferably join without a fillet to form an apex 68. The apex defines one "end" of the hole 16 in the body wall (in case the hole is of elongated form as shown in Fig. 6), the opposite end being conveniently formed as a semicircular portion 69 merging at its ends with the respective sides 67. Thus the effective metering orifice or port 16a (regardless of variations in port size) has a fixed axis which is determined by the direction in which the apex points, and another which varies in position but points up the mixing tube generally centrally of it in all relative positions of the two valve-forming parts 20 and 22.

As will be apparent from comparison of Figs. 6 and 8, in all open positions of the metering valve the thin edge walls 67 of hole 16 establish the most restricted portion of the gas path from the valve chamber 21 into the mixing tube and constitute the major part of the effective metering orifice boundary. To make those walls 67 as thin as practically possible near the apex, so that the perimeter surface of the orifice will have a near minimum frictional restraint on the issuing gas, and particularly at low gas settings, the top side of the body 20 is milled off approximately parallel to the axis of the bore 21 so that the orifice boundary wall thickness (measured in the direction of the gas stream axis) is relatively thin as compared, for example, to the side dimensions of the effective orifice when the same is so nearly closed that the volume of gas supplied is too small to support a stable flame at the burner flame port 17. In the disclosed burner, the edge of the hole 16 as cut by section line 8-8 in Fig. 6 is about .010" (hole in that plane being about .100" wide) and, as will be apparent, the thickness of the edge diminishes gradually toward the apex from the widest part of the hole (i. e. measured along plane 8-8). There is nothing particularly critical about the actual orifice edge thickness except that the thinner it is the lower the turn-down ratio of the burner can be. The construction, subject to limits imposed by usable materials and production methods, thus permits

the edge thickness to be almost infinitely small.

The angle of convergence of the sides 67 of hole 16, as shown is fairly narrow for obvious constructional reasons (width of flat limited). Further to reduce the perimeter, hence the boundary area, of the orifice for a given effective port area the acting sides 67 would measure the same as the acting metering edge of the valve plug, or in other words the effective orifice or port 16a would be an equilateral triangle in all metering positions of the valve.

It will be noted, in Fig. 6, that when the skirt of the cup 22 (which forms a cavitated end of the valve plug and part of the essential valve chamber in the illustrated form of valve) meets the annular seat 28 of gas conducting sleeve 26, the skirt and sleeve are of the same internal diameter. That is one way of making the effective valve-chamber-forming surfaces which conduct the gas directly to the orifice 16a, regardless of how far open the valve is, bisymmetrical about the operating axis of the effective orifice, so that the stream of gas as it issues from the orifice will never be deflected laterally of the mixing tube or against any "spoiling" surface such as would decrease the velocity of the stream.

The valve member 22 is slidably operable in the valve chamber 21 in covering relation to the hole 16 and the orifice or triangular effective metering port 16a is opened by movement of the valve member toward the right as seen in Fig. 2 to uncover a portion of the hole of variable size depending upon the extent to which the valve member is moved. The valve member 22 can be of any suitable construction, but is preferably in the form of a resiliently flexible cup, as here shown, whose bottom end is connected with the valve shaft 30 and whose skirt portion 22a is slidably in the valve chamber 21 and has annular sealing engagement therewith at all times. The valve member 22 can be made of any suitable material such as a graphite impregnated synthetic rubber and can be molded to the desired shape. Although the valve member 22 is preferably made of a resilient material as just mentioned, it could, if desired, be made of a hard or rigid material such as metal or a rubber or resin composition. As shown in Fig. 8, the bore providing the valve chamber 21 is located in the arm portion 25 of the frame and adjacent the top thereof so that the metal remaining at the top of the arm portion will provide relatively thin edge portions 70 which extend around and define the opening of the hole 16 and of the orifice 16a and taper to a thickness of approximately ten thousandths of an inch at the edge of the orifice opening.

With the construction and arrangement above described for the orifice 16a and the valve member 22, it will be seen that when the valve member is shifted toward the right as the result of counter-clockwise rotary movement imparted to the control shaft 13, the skirt portion 22a will uncover or open the orifice 16a to permit a nearly constant velocity stream of gas to be discharged therethrough into the burner tube 12. During the opening movement of the valve member 22 the orifice 16a increases progressively in size in accordance with two variable functions. One of these functions is the movement of the valve member 22 away from the apex 68 which increases the size of the orifice 16a by increasing the length thereof. The other function is the diverging relation of the sides 67 which also causes a progressive increase in the transverse width of the orifice 16a during the opening move-

ment of the valve member. It will thus be seen that the orifice 16a increases in size in two different dimensional directions during the opening movement of the valve member 22.

This variable size characteristic of the orifice 16a bears an important relation to the gaseous fuels of different B. t. u. values which may be supplied to the burner. Thus when a gaseous fuel of a very low B. t. u. value such as artificial gas is supplied to the burner, a relatively large volume flow of this gas is needed to maintain operation of the burner at a desired flame height or heat output. When the control shaft 13 is rotated through an angular distance sufficient to result in an opening of the control valve 14 for producing the desired flame height, the valve member 22 will uncover a greater length of the hole 16 and the greater the length of the uncovered portion of the hole the greater will be the extent to which the orifice 16a is enlarged, due to the diverging relation of the sides 67. On the other hand, when a gaseous fuel of high B. t. u. value is being supplied such as butane, only a small orifice opening is needed because a gas stream of only relatively small volume will be sufficient to produce the desired flame height or heat value. Therefore, while the butane gas is being supplied, the hole 16 is uncovered for only a small portion of its length and the diverging relation of the sides 67 will produce only a small amount of increase in the size of the orifice 16a.

The main burner 10 is provided with a suitable pilot burner 12 which will be described next. The pilot burner 12 is mounted on the upright arm portion 19 of the frame 11 and comprises a pilot burner tube 73 located adjacent the lower end of the shutter member 15. Gas is supplied to the pilot burner tube 73 from the inlet chamber 24 through a passage 14 and a filter chamber 75. A body of permeable material such as fibrous asbestos, glass wool, rock wool, felt or other suitable material is disposed in the chamber 75 and forms a filter element 76 therein through which the gas passes and which serves to remove foreign matter which might extinguish or impair the pilot burner flame. The amount of gas flowing to the pilot burner 12 can be controlled and adjusted by varying the density of the filter element 76. This can be accomplished by adjustment of the screw plug 77 which acts to apply a compressive force to the filter element.

For the purpose of conducting an ignition flame from the pilot burner 12 to the delivery opening 17, the shutter member 15 is provided with a series of small ignition holes 78. The ignition holes 78 are in communication with an axially extending space 79 extending between the shutter member and the burner tube 12 and to which a gas and air mixture is supplied through openings 80 formed in the burner tube adjacent its upper end. Adjacent the upper end of the shutter member 15, one or more ignition holes 78a are in communication with the axial passage of the shutter member and will be supplied with a gas and air mixture directly therefrom.

When the burner 10 is initially turned on it is desirable that the valve member 22 be opened to a small extent prior to the opening or enlargement of the combustion opening 17. This is desirable so that a gas stream will be discharged into the burner tube 12 and will produce a gas and air mixture to be supplied to the ignition holes 78 prior to the movement of the shutter 75

member 15 away from the cap 43. This will insure a proper ignition flame being available at the delivery opening 17 at the beginning of the issuance of the gas and air mixture stream therefrom. This advance opening of the valve member 22 in timed relation to the movement of the shutter member 15 can be obtained by adjustment of the nut 58 of the valve stem 30 and also by providing a dwell portion or flat 50a on the cam 50, as shown in Fig. 4. Initial rotary movement of the shaft 13 in turning on the burner will cause opening movement to be imparted to the valve member 22 while the dwell portion 50a of the cam maintains the shutter member 15 in its lifted position for temporarily maintaining the combustion opening 17 closed.

The adjustment of the timing of the opening of the valve member 22 with respect to the opening of the combustion orifice 17, is accomplished by means of the adjusting nut 58 and the cam flat 50a, as explained above, but variation in the amplitude of the opening movement imparted to the valve member in relation to the opening of the combustion orifice is obtained by shifting the fulcrum bar 62 by means of the adjusting screw 64. Thus when a gas of high B. t. u. value is to be burned, the fulcrum bar 62 will be lowered to decrease the amplitude of movement of the valve member 22 so that the orifice 16a will be opened to only a small extent for a given rotary movement of the shaft 13. Conversely, when a gas of low B. t. u. value is to be burned the fulcrum bar is raised to increase the amplitude of movement of the valve member.

It is necessary that the ignition holes 78 be located in a position approximately directly above the pilot burner 12 and in order to maintain this relation, the shutter member 15 is held against rotation. This can be accomplished by the cam follower 56 which extends into a slot 81 of a forked portion provided on the upper end of the arm portion 18 of the frame and acts as a holding lug.

For certain operating conditions of the burner 10, it may be desirable to decrease or vary the amount of combustion air admitted to the burner tube 12 through the air inlet openings 40. For example, when gas of a high B. t. u. value is being supplied the velocity gas stream discharged by the orifice 16a will be of relatively small volume and will require only a small volume of combustion air. The burner 10 is accordingly provided with a pair of air control cover members 82 and 83 which are pivotally mounted on the frame 11 and located at opposite sides thereof in overlying relation to the air inlet openings 40. These cover members can be substantially flat sector-shaped members as shown in the drawings and one of these members, in this instance the cover member 82, is provided with an actuating arm or lug 84. An adjusting screw 85 extending through a threaded opening 86 of the frame 11 cooperates with the lug 84 for holding the cover members 82 and 83 at a desired position of adjustment.

The cover members 82 and 83 are preferably not mounted directly on the frame 11 but on a pivot shaft 87 against the ends of which they are firmly secured by the clamping screws 88. The shaft 87 is rockable in an opening of the frame 11 and provides a connection between the two cover members 82 and 83 so that an adjusting force applied to the lug 84 of the cover member 82 by the screw 85 will be effective on both cover members. With the arrangement just described for the cover members 82 and 83, it will be seen that

the removal of the burner tube 12 from the frame 11 for cleaning or other purposes, and the replacement thereof, will not disturb the setting to which the cover members have been adjusted by the screw 85.

Figs. 12 to 17 inclusive illustrate a gas burner 90 which is of the same general type as the burner 10 above described, but represents a modification thereof. The modified burner 90 includes a frame 91 on which the burner tube 92 is mounted in upright relation above the gas delivery orifice 93 of the control valve 94. A shutter member 95 in the form of a sleeve surrounds the burner tube 92 and is axially movable relative thereto for controlling the annular delivery opening 96 provided at the top of the burner for the gas and air mixture. The burner 90 also includes a manually operable control shaft 97 which has both rotary and axial movement. The gas delivery orifice 93 embodies the novel shape described above for the hole 16 and the orifice 16a.

A cam 98 mounted on the inner end of the shaft 97 utilizes the rotary movement of this shaft for actuating the shutter member 95 by engagement with the lug or follower 95a of the shutter member to thereby vary the size of the combustion opening 96. A rockable lever 99 utilizes the axial movement of the shaft 97 for actuating the gas control valve 94. The gas control valve 94 comprises a valve chamber 103 formed as a bore in the frame 91 and a valve member 101 disposed in covering relation to the gas delivery orifice 93 and slidably movable in the valve chamber. The valve member 101 is carried by a valve stem 102 whose outer end is operably connected with the lever 99. A compression spring 103 disposed around the valve stem acts to urge the valve member 101 toward engagement with an annular valve seat 104. A bar 105 forms a fulcrum for the lever 99 and is adjustable in the vertical slots 106 of the frame 91 for varying the lever arm values of the lever 99. The bar 105 is adapted to be locked in different positions of vertical adjustment by means of the clamping screws 107 which are mounted in the ends thereof.

The frame 91 has a gas supply passage 109 therein which communicates with the bore 100 through a radial port 110. A sleeve 111 extends into the bore 100 in a snugly fitting relation and has the valve seat 104 formed on the inner end thereof. The axial passage 112 of the sleeve 111 connects the valve chamber 100 with a radial port 113 which is formed in the sleeve and cooperates with the radial port 110 of the frame. The radial ports 110 and 113 together form a valve which is adapted to be actuated by rotary adjustment of the sleeve 111 in the valve chamber 100. The sleeve 111 has an integral head 114 thereon and can be accurately adjusted by a suitable tool applied to the non-circular portion 114a of such head. The sleeve is retained in the bore of the valve chamber 100 by means of a retaining cover 115 which overlies the head 114 and is attached to the frame 91 as by means of the screw 116. A sealing washer 117 is preferably provided between the head 114 and the adjacent face of the frame 91.

The modified burner 90 is provided with suitable pilot burner means which is mounted on the frame 91 at one side of the main burner tube 92. The pilot burner means comprises a continuously burning pilot burner 119 and an intermittently burning pilot burner 120. The pilot burner 119 is continuously supplied with gas through a passage 121 whose lower end is in com-

munication with a groove 122 surrounding the sleeve 111 and which groove is constantly in communication with the port 110 so as to receive gas therefrom. The passage 121 includes a filter chamber 123 containing a body of permeable fibrous filtering material such as fibrous asbestos. The flow of gas to the pilot burner 119 can be varied or controlled by varying the density of the filtering material 124 and this is accomplished by variable pressure applied thereto by means of the screw plug 125.

The intermittently burning pilot burner 120 includes a burner tube 126 extending upwardly alongside the shutter member 95 and having a series of ignition holes 127 extending through the wall thereof on the side adjacent the continuously burning pilot burner 119. The pilot burner 120 is supplied with gas through a passage 128 and a filter chamber 129. The passage 128 is connected with a groove 130 which extends around the sleeve 111 and which groove is, in turn, connected with the valve chamber 100 by means of an axial passage 131. The groove 130 is separated from the groove 122 by an annular land formed by an intervening portion 132 of the sleeve 111.

When the burner 90 is turned on, the opening of the valve member 101 permits gas from the valve chamber 100 to flow through the axial passage 131 to the annular groove 130 from which it is supplied to the burner tube 120 through the passage 128 and the filter chamber 129. A body of suitable fibrous material contained in the filter chamber 129 forms a filter medium 133 through which the gas flows and which serves to remove objectionable foreign matter. The filter medium 133 is subjected to compression by a plug 134, similar to the plug 125 mentioned above, and its density is thereby varied for controlling the flow of gas to the pilot burner 120. The gas which is supplied to the pilot burner 120 by the turning on of the main burner 90 causes small streams of gas to be discharged laterally through the ignition holes 127 and when these streams are ignited the ignition flame is conducted from the continuously burning pilot 119 to the combustion opening 96 for igniting the gas and air mixture issuing from the latter.

In the burner 90 described above, the delivery opening 96 is defined by the upper end of the shutter member 95 and the cap 134 supported thereabove. The cap 134 is a disk-like member which is mounted on the burner tube 92 by means of the axial post 135 and a ribbon portion 136 formed by a strip of metal partially sheared from the upper end of the burner tube.

Figs. 18, 19 and 20 show another modified burner 140 which is the same as the burner 10 of Figs. 1 to 11 inclusive, except that the shutter sleeve of the burner tube is reversed from the arrangement used in the burner 10, and consequently, the cap 43 and the cam follower 56 of the shutter actuating means are arranged somewhat differently. In other respects the modified burner 140 is substantially the same as the burner 10 and the same reference characters have been used on the corresponding parts.

In the modified burner 140 the burner tube 141 is an upright sleeve mounted on the frame 11 in the manner explained above for the sleeve 12 of the burner 10, and the shutter member 142 is a sleeve slidable in the burner tube and whose upper end is movable relative to the cap 43 for controlling the combustion opening 17. The cap 43 is mounted in fixed relation on the upper end of the burner tube 141 as by means of the circum-

ferentially spaced integral axial extensions 143 to which the cap is welded or otherwise secured. The end portions of the shutter member 142 provide the bearing surfaces 144 and 145 which are slidable in corresponding end portions of the burner tube 141. The intermediate portion of the shutter member 142 is of a reduced size and cooperates with the burner tube to provide therebetween the above-described axial space or passage 79 for supplying a gas and air mixture to the ignition holes 78. The cam follower 56 is connected to the shutter member 142 and extends outwardly through a slot 146 of the burner tube 141 for cooperation with the cam 50.

From the foregoing description and the accompanying drawings it will now be readily understood that this invention provides an improved gas burner which can be economically manufactured and assembled and which will be safe and reliable in operation. It will also be understood that the improved burner is well suited for use in stoves and the like and will operate efficiently and with a very satisfactory turndown ratio on different types of gaseous fuels having widely varying B. t. u. values without requiring any alteration or substitution of burner parts. Additionally, it will be seen that in the improved burner a pair of control members comprising a shutter member and a gas control valve are actuated from the same control shaft by utilizing rotary movement of the shaft to actuate one of the control members and utilizing axial movement of the shaft for actuating the other control member. It will now also be recognized that the use of a gas delivery orifice of a divergent shape in the improved burner renders the orifice self-regulating as to flow capacity and that this is an important feature in adapting the burner for operation on gases of different B. t. u. values.

Although the improved burner construction provided by this invention has been illustrated and described herein to a detailed extent, it will be understood, of course, that the invention is not to be regarded as being limited correspondingly in scope but includes all changes and modifications coming within the terms of the claims hereof.

Having thus described our invention, we claim:

1. A gas burner comprising, a mixing tube having an air inlet opening and a delivery opening for a gas and air mixture, a base having a valve bore therein adapted to be supplied with gas under pressure and also having an orifice forming a substantially radial outlet port for said bore and located so as to discharge a single velocity stream of gas in said tube for mixing with air from said inlet opening, a valve member operable in said bore for turning the burner full on and off and for varying the volume of said stream of gas between the full on and off positions, said valve member being disposed in said bore in controlling relation to said orifice and being slideable in said bore axially thereof for variably opening said orifice, and means for actuating said valve member, said orifice having an apex at one end and being elongated axially of said bore and in the direction of opening movement of said valve member and having a taper which diverges in the direction of said opening movement, the portions of said base surrounding said orifice being tapered so as to decrease in thickness to a relatively thin edge around the perimeter of the orifice opening.

2. A gas burner as defined in claim 1 in which said valve member is a cup-shaped resiliently flexible member having an imperforate skirt por-

tion longitudinally slidable in said bore during said opening movement.

3. A gas burner comprising, a one-piece frame having lateral and upright arm portions, a hollow burner element mounted on said frame and extending in upright relation above the lateral arm portion thereof, said burner element being provided with an air inlet opening at its lower end and also having a delivery opening for a gas and air mixture, said lateral arm portion having a bore therein extending transversely of the burner element axis and adjacent said lower end and adapted to be supplied with gas under pressure and also having an orifice therein located to discharge a stream of gas from said bore radially thereof into said lower end of said burner element for mixing with air from said air inlet opening, a pair of control members comprising a movable valve member carried by said lateral arm portion and movable in said bore for controlling said orifice and a shutter member movable relative to said burner element for varying said delivery opening, a shaft operably mounted on said upright arm portion, and motion transmitting means for causing actuation of said valve member and shutter member in response to operation of said shaft, said frame forming a common mount supporting said burner element, said control members, said shaft and said motion transmitting means in cooperative relation in a compact assemblage.

4. A gas burner comprising, a one-piece frame having lateral and upright arm portions, a hollow burner element mounted on said frame and extending in upright relation above the lateral arm portion thereof, said burner element being provided with an air inlet opening at its lower end and also having a delivery opening for a gas and air mixture, said lateral arm portion having a bore therein extending transversely of the burner element axis and adjacent said lower end and adapted to be supplied with gas under pressure and also having an orifice therein located to discharge a stream of gas from said bore radially thereof into said lower end of said burner element for mixing with air from said air inlet opening, a pair of control members comprising a valve member axially movable in said bore and controlling said orifice and a shutter member movable relative to said burner element for varying said delivery opening, a shaft rotatably mounted on said upright arm portion, cam means supported by said frame to be actuated by said shaft for imparting said axial movement to said shutter means, and lever means adapted to be actuated by said shaft for imparting movement to said valve member, said frame forming a common mount supporting said burner element, said control members, said shaft, said cam means and said lever means in cooperative relation in a compact assemblage.

5. A gas burner comprising, a one-piece frame having lateral and upright arm portions, a hollow burner element mounted on said frame and extending in upright relation above the lateral arm portion thereof, said burner element being provided with an air inlet opening at its lower end and also having a delivery opening for a gas and air mixture, said lateral arm portion having a bore therein extending transversely of the burner element axis and adjacent said lower end and adapted to be supplied with gas under pressure and also having an orifice therein located to discharge a stream of gas from said bore into said burner element for mixing with air from said

air inlet opening, a pair of control members comprising an axially movable valve member carried by said lateral arm portion and controlling said orifice and a shutter member movable relative to said burner element for varying said delivery opening, a shaft mounted on said upright arm portion for rotary and axial movement, cam means responsive to the rotary movement of said shaft for imparting movement to said shutter member, cooperating screw elements on said shaft and upright arm portion for causing said axial movement of the shaft during the rotary movement thereof, and lever means supported by said frame and responsive to the axial movement of said shaft for imparting the axial movement to said valve member, said frame forming a common mount supporting said burner element, said control members, said shaft, said cam means, said screw elements and said lever means in cooperative relation in a compact assemblage.

6. A gas burner comprising, a frame having lateral and upright arm portions, a hollow burner element mounted on said frame and extending in upright relation above the lateral arm portion thereof, said burner element being provided with an air inlet opening and a delivery opening for a gas and air mixture, said lateral arm portion having a bore therein adapted to be supplied with gas under pressure and also having an orifice therein located to discharge a stream of gas from said bore into said burner element for mixing with air from said air inlet opening, a pair of control members comprising a movable valve member operable in said bore for controlling said orifice and a shutter member movable relative to said burner element for varying said delivery opening, a shaft rotatably mounted on said upright arm portion, a rotary cam actuated by said shaft for imparting movement to said shutter member, a lever adapted to be rocked by said shaft for imparting movement to said valve member, a fulcrum on which said lever is rockable and which fulcrum is adapted to be adjustably positioned for varying the effectiveness of said lever, and adjusting means for positioning said fulcrum.

7. In a gas burner of the type having a mixing tube provided with an air inlet opening and a delivery opening for a gas and air mixture, means providing a tubular valve chamber having a substantially radial orifice for discharging a velocity stream of gas in said tube so as to induce a flow of air through said inlet opening for mixing with the gas, a pair of control members comprising a shutter member movable relative to said tube for varying said delivery opening and a valve member for controlling the discharge of gas through said orifice, cam means adapted to impart movement to one of said control members, lever means adapted to impart movement to the other of said control members, and a rotary shaft adapted to actuate said cam means and said lever means, said orifice having an apex at one end and being elongated in the direction of opening movement of said valve member and having a tapering width which diverges in the direction of said opening movement, said valve member being in said valve chamber in controlling relation to said orifice and being reciprocable in said valve chamber axially thereof, the portions of said means surrounding said orifice being tapered so as to decrease in thickness toward the orifice and substantially radially of said valve chamber to a relatively thin edge around the perimeter of the orifice opening.

8. In a gas burner, a frame having lateral and upright arm portions, a burner tube mounted on

said frame and extending in upright relation above said lateral arm portion, said burner tube having an air inlet opening at its lower end and being provided at its upper end with a delivery opening for a gas and air mixture, said lateral arm portion having a bore therein adapted to be supplied with gas under pressure and also having a single substantially radial orifice located to discharge a velocity gas stream into said burner tube so as to induce a flow of air through said inlet opening for mixing with the gas, a pair of control members comprising a shutter member movable relative to said burner tube for varying said delivery opening and a valve member reciprocably slidable in said bore in controlling relation to the orifice for controlling the discharge of gas from said orifice, a shaft mounted on said upright arm portion for simultaneous rotary and axial movement, a cam driven by said shaft and adapted to actuate said shutter member in response to the rotary movement of said shaft, and a lever rockably mounted on said upright arm portion and adapted to actuate said valve member in response to the axial movement of said shaft, said orifice being elongated in the direction of opening movement of said valve member and having a taper which diverges in the direction of said opening movement.

9. In a gas burner, a frame having lateral and upright arm portions, a burner tube mounted on said frame and extending in upright relation above said lateral arm portion, said burner tube having an air inlet opening at its lower end and being provided at its upper end with a delivery opening for a gas and air mixture, said lateral arm portion having a chamber therein adapted to be supplied with gas under pressure and also having an orifice located to discharge a gas stream into said burner tube so as to induce a flow of air through said inlet opening for mixing with the gas, a pair of control members comprising a shutter member movable relative to said burner tube for varying said delivery opening and a valve member reciprocably movable in said chamber for controlling the discharge of gas from said orifice, a shaft mounted on said upright arm portion for simultaneous rotary and axial movement, a cam driven by said shaft and adapted to actuate said shutter member in response to the rotary movement of said shaft, a lever carried by said upright arm portion and adapted to actuate said valve member in response to the axial movement of said shaft, means providing an adjustable connection between said lever and valve member, and fulcrum means rockably mounting said lever on said upright arm and being adjustable for varying the lever arm values of said lever.

10. In a gas burner, a support, an upright burner tube on said support and adapted to be supplied with air and gas at the lower end thereof and at its upper end having a delivery opening for a gas and air mixture, a shutter sleeve disposed in telescoping relation around said burner tube and being axially movable for varying said delivery opening, said burner tube and sleeve having a space extending axially therebetween and said burner tube having an opening therein for supplying some of said mixture to said space, and a pilot burner mounted on said support adjacent said lower end of the burner tube and adapted to be continuously supplied with gas, said sleeve having holes therein communicating with said space and disposed in a

series extending between said pilot burner and said delivery opening.

11. In a gas burner, a frame, a burner tube mounted on said frame and having an air inlet opening and a delivery opening for a gas and air mixture, said frame having a bore therein and also having an orifice therein and located in the side wall of said bore for discharging gas from said bore substantially radially thereof into said tube for mixing with air from said air inlet opening, a valve member axially movable in said bore for controlling the discharge of gas from said orifice, a sleeve in said bore and through which the gas is adapted to be supplied to said orifice, said sleeve and frame having cooperating elements thereon forming a second valve for controlling the flow of gas through the sleeve and said sleeve being arcuately movable in said bore for actuating said second valve, and a valve seat on the inner end of said sleeve and adapted to be engaged by said valve member when the latter is in the position for preventing the discharge of gas from said orifice.

12. In a gas burner, a frame, a burner tube mounted on said frame and having an air inlet opening and a delivery opening for a gas and air mixture, said frame having a bore therein and also having an orifice for discharging gas from said bore into said tube for mixing with air from said air inlet opening, a valve member movable in said bore for controlling the discharge of gas from said orifice, a sleeve in said bore and through which the gas is adapted to be supplied to said orifice, a valve seat on the inner end of said sleeve and adapted to be engaged by said valve member when the latter is in the position for preventing the discharge of gas from said orifice, a continuous pilot burner adjacent said burner tube, means for supplying gas continuously to said continuous pilot burner, an intermittent pilot burner adapted to transmit flame from said continuous pilot burner to said delivery opening, and means providing a gas supply passage between said sleeve and frame leading to said intermittent pilot burner and adapted to receive gas from said sleeve when said valve member is moved away from said seat.

13. A gas burner for burning fuel gases of different B. t. u. values comprising, a base having a tubular valve chamber therein adapted to be supplied with gas under pressure, a substantially straight mixing tube having one end connected with said base for mounting the tube thereon with its axis extending substantially normal to the axis of said valve chamber, said tube having an air inlet opening at said one end and at its other end having a delivery opening for a gas and air mixture, said base having an orifice therein leading from said valve chamber substantially radially thereof and located substantially on the axis of said mixing tube and adapted to discharge a velocity stream of gas in the latter for mixing with air induced through said air inlet opening, a valve member in controlling relation to said orifice and being movable in said valve chamber axially thereof for turning the burner full on and off and for partially opening the orifice, and means for actuating said valve member, said orifice having an apex at one end and being tapered axially of the valve chamber such that the portion of the orifice uncovered by said valve member varies progressively in width with the axial movement of the valve member, the portions of said base surrounding said orifice being tapered so as to decrease in

thickness toward the orifice and substantially radially of said valve chamber to a relatively thin edge around the perimeter of the orifice opening.

14. A gas burner of the character described comprising, a base having a tubular valve chamber therein adapted to be supplied with gas under pressure, a mixing tube having one end thereof connected with said base, said mixing tube having an air inlet opening at said one end and at its other end having a delivery opening for a gas and air mixture, said base having an orifice therein leading from said valve chamber substantially radially thereof and adapted to discharge a velocity stream of gas in said tube for mixing with air induced through said air inlet opening, said orifice being of diverging shape axially of said valve chamber, an annular valve seat in said valve chamber adjacent one end of said orifice, a valve member in said valve chamber in controlling relation to said orifice and having a closed position in engagement with said seat, said valve member being axially shiftable in said valve chamber for opening and closing movement relative to said seat and for variably opening said orifice, and means operable to impart axial movement to said valve member.

15. A gas burner for burning fuel gases of different B. t. u. values comprising, a base having a tubular valve chamber therein adapted to be supplied with gas under pressure, a mixing tube having one end thereof connected with said base for mounting the tube thereon with its axis extending substantially normal to the axis of said valve chamber, said tube having an air inlet opening at said one end and at its other end having a delivery opening for a gas and air mixture, said base having an orifice therein leading from said valve chamber substantially radially thereof and located substantially on the axis of said mixing tube and adapted to discharge a velocity stream of gas in the latter for mixing with air induced through said air inlet opening, said orifice having an apex portion at one end and a diverging taper extending away from said apex portion and axially of said valve chamber, an annular valve seat in said valve chamber adjacent said apex portion, a valve plunger in said valve chamber in controlling relation to said orifice and having an annular end portion engageable with said annular valve seat in the closed position of the valve plunger, said valve plunger being axially slidabie in said valve chamber for opening and closing movements relative to said seat and for opening said orifice to a variable extent, and means operable to impart axial movement to said valve plunger.

16. In a gas burner, a mixing tube having an air and gas inlet end and an outlet end for discharge of mixed air and gas, a metering valve arranged for controllably admitting gas into the inlet end as a single concentrated stream of approximately constant velocity for aspiration of air into the mixing tube therewith, the valve comprising two relatively movable parts, forming a valve chamber, namely, a hollow body for conduction and confinement of the gas under pressure, a portion of the wall of the body, the exterior surface of which portion is presented toward the mixing tube inlet, having a hole therethrough whose axis extends into the mixing tube longitudinally of the tube and which hole has two very thin boundary wall surface portions converging to form an apex, and a valve member inside said hollow body and forming with said converging surfaces a variable metering orifice, together

with means for relatively moving the hollow body and the valve member back and forth along the direction in which the apex points.

17. A gas burner according to claim 16 wherein in the valve-chamber-defining walls leading to the orifice are approximately bisymmetrical about the orifice axis, whereby the direction of the stream of gas issuing from the orifice is not materially altered by relative movement of said metering-valve-forming parts from maximum to minimum flow-controlling positions of the parts.

18. In a gas burner, a mixing tube having an air and gas inlet end and an outlet end for mixed air and gas, a metering valve arranged for admitting a single concentrated stream of gas into the inlet end of the tube parallel to the direction of extent of said end for aspiration of air into the tube with the gas, the valve comprising two relatively movable parts, namely a hollow body for conduction and confinement of the gas under pressure and having a port-forming orifice in its wall, and a cooperating part inside the body and having a metering edge portion for variably restricting the orifice, said orifice having converging surfaces meeting to form an apex, and the cooperating part being guided or constrained to move back and forth in the direction in which the apex points so that the stream of gas issuing from the orifice can be gradually changed in cross-section in two directions simultaneously without substantial change in stream cross-sectional form, the converging surfaces lengthwise of the stream axis being generally of less extent than the smallest side dimension of the port through which the stream issues in practically all metering relative positions of the two valve-forming parts, so that the air-aspirating stream velocity is not reduced by restriction of the effective orifice area to a usable minimum.

19. In a gas burner, a mixing tube having an air inlet end and a gas and air outlet end, a metering valve tube, means supporting the tubes in transverse juxtaposition, the interior of the metering valve tube, in approximate alignment with the air inlet end of the mixing tube, forming a valve chamber and the portion of the metering valve tube wall adjacent said inlet end of the mixing tube having a gas-port-forming hole through it for admitting gas from the valve chamber into and along the mixing tube as a concentrated single stream, the hole being defined in part by relatively converging tube-wall-forming apically connected edge surfaces pointing in the general direction of the metering valve tube axis, a plug slidably fitting the interior of the metering valve tube in position to open and close the port, valve tube in position to open and close the port, means for relatively moving that tube and the plug along their common axis variably to open and close the port, whereby to vary the transverse dimensions of the stream in two directions without substantially changing its cross-sectional form, the metering valve tube and plug having approximately bisymmetrical about the gas delivery axis of the port, so that the direction of flow of the gas stream into the mixing tube is not changed materially during variation of the effective port area.

20. The gas burner apparatus according to claim 19, wherein the radial dimensions of portions of the converging gas-port-forming surfaces of the metering valve tube adjacent the apex are

reduced relative to the radial dimensions of other portions of the port-defining surfaces, whereby, as the gas stream admitted through the port is reduced in cross-section with valve-port-closing relative movement of the plug and metering valve tube, the extent of gas-contacting surface co-directionally of the stream axis diminishes.

21. In a gas burner, a mixing tube having an air inlet end and a gas and air outlet end, a metering valve tube, means supporting the tubes transversely of and in proximity to each other, a wall portion of the metering valve tube forming a perimetral portion of a valve chamber and that portion of said wall having an orifice therethrough whose axis is directed into the inlet end of the mixing tube for discharge of a single stream of gas into that tube generally parallel to its axis, side-defining, relatively converging walls of the orifice joining to form substantially an apex, a plug slidably fitting the metering valve tube, means for relatively moving that tube and the plug along their common axis away from and toward said apex variably to open and substantially close the orifice, means adapted to conduct gas into the valve chamber, said means forming an annular valve seat adjacent to the apex, the plug having a cooperating annular end surface portion engaging the seat when the plug and metering valve tube are relatively moved a predetermined distance in the direction to close the orifice.

22. The apparatus according to claim 21, wherein the plug has a cavity facing said annular valve-seat-forming means, and the plug and annular means have approximately the same inner diameter in the seating plane, whereby the direction of the stream of gas issuing through the orifice from between the plug and seat is approximately unchanged by separating movement of the plug and seat.
